United States Patent Office.

H. A. DEVENDORF, OF PORT JACKSON, NEW YORK.

Letters Patent No. 91,096, dated June 8, 1869.

IMPROVED PAPER BOX.

The Schedule referred to in these Letters Patent and making part of the same.

To all whom it may concern:

Be it known that I, H. A. DEVENDORF, of Port Jackson, in the county of Montgomery, and State of New York, have invented a new and useful Improvement in Paper Boxes; and I do hereby declare that the following is a full, clear, and exact description of the construction and operation of the same, reference being had to the accompanying drawings, making a part of this specification, in which—

Figure 1 is a plan;

Figure 2, a side elevation;

Figure 3, a top view; and

Figure 4, a side elevation, the several drawings representing the different stages of the process of manufacturing a paper box by my improved method.

This invention relates to an improvement in the manner of constructing paper boxes, whereby they can be made more economically, and with less labor, while the article produced will be stronger and more substantial than the boxes hitherto made of the same material.

My improved process consists in cutting the paper into rectangular strips A B, and placing them in the position shown in fig. 1, one lying across the other. The width of each strip is equal to the diameter of the box to be formed, and the length of each strip is equal to said diameter, plus twice the height of the side of the box.

Having cut out the strips in this form, and placed them as described, I trace a line, c c, to guide in forming the bottom of the box, and then slit the sides of the pieces A B, from the corners where their edges intersect, in a direction tangent, or nearly tangent to each side of the circle c, as shown at e e.

That part of each strip between the line c and the slits e e is then bent up around the curved line, forming an upright angular piece, as shown at E E, fig. 2.

The ends of the upper strip are then bent up to a vertical position, as shown at B B, fig. 2, and are bent round to fit the curve c c, overlapping the lips E E, to which they are substantially glued.

The ends of the lower strip A are then bent up, and bent to fit around the circle c in the same manner, overlapping along their vertical edges the edges of the inner piece B, to which they are firmly attached by some suitable glue or adhesive gum. The box is then finished and ready for use.

The box is shown with three sides formed, in fig. 4, and in fig. 3 the relative positions of the different parts can be clearly seen by the brown, red, and blue lines.

It is evident that the thickness and strength of the box can be increased to any extent, by building up the walls and bottom in this way.

It is further evident that the box can be made octagonal or polygonal in shape, if preferred.

Having thus described my invention,

What I claim as new, and desire to secure by Letters Patent, is—

As a new article of manufacture, a paper box, constructed by means of the strips A B, slit at e e, and bent up and attached together, substantially in the manner specified.

To the above specification of my improvement, I have signed my hand, this 20th day of July, 1868.

H. A. DEVENDORF.
